UNITED STATES PATENT OFFICE

LUCIAN B. SMITH, OF FLINT, MICHIGAN, ASSIGNOR TO A C SPARK PLUG COMPANY, OF FLINT, MICHIGAN, A COMPANY OF MICHIGAN

PULSATATOR FOR FUEL PUMPS

Application filed June 28, 1928. Serial No. 289,049.

This invention relates to systems for the delivery of liquid fuels, as required by internal combustion engines used upon motor vehicles, or the like, and the pulsator referred to is suitable to be used upon, or in replacement of, the outlet valve plug of a variable stroke fuel pump,—such as for example, the fuel pump disclosed in an application by Abraham M. Babitch, Serial No. 123,370, filed July 19, 1926.

It is an object of this invention to provide a novel flow-equalizing unit, especially suitable for use in a fuel delivery line, but in whose operation little or no reliance is placed upon the use of resilient metallic parts.

Various uses of a lenticular pulsator unit externally and generally resembling that upon which protection is herein sought have been described and claimed in an application by Joseph Zubaty and Abraham M. Babitch, S. N. 288,755, filed June 27, 1928 (B-10,114); but the present invention differs in principle therefrom in that use is herein made of a so-called "slack-cloth" or similar diaphragm, rather than a metallic or other resilient diaphragm—air pressure being admitted to the outer surface of the non-resilient diaphragm referred to, even though said surface be protected by a downwardly concave guard resembling that disclosed in the Zubaty et al. application, but perforated or formainous.

Broadly, it is an object of this invention to provide means, preferably suitable for use in replacement of a valve plug, permitting some utilization of any momentum, such as the momentum that may be intermittently imparted to a liquid fuel by a reciprocatory fuel pump, in promoting a continuous advance of pumped fuel through some part of a fuel line; and it is an especial merit of the construction herein described that the use of the mentioned fabric diaphragm, or its equivalent, renders the pulsator unit containing the same highly sensitive to pressure differentials. For the foregoing reasons, the pulsator herein described and claimed is referred to as an inertia-effect pulsator.

Other objects of this invention, which may be broadly described as comprising a hollow body to whose interior liquid fuel is ad-

mitted, this body being provided with an upwardly concave part serving to support the mentioned non-resilient diaphragm and said diaphragm being optionally protected by a perforated and downwardly concave guard element which serves also to secure the edges of said diaphragm to said support, may be best appreciated by the following description of a specific embodiment thereof, taken in connection with the appended claims and the accompanying drawing.

The figure is, for the most part, a vertical median section through a variable-stroke reciprocating fuel pump equipped with a pulsator embodying my invention.

Referring first to the conventional features shown in the mentioned drawing, a main pump casting 10 is shown as associated with a closure plate or casting 11; and one of these castings may comprise a pump chamber 12 whose volume is variable by reciprocation of a pumping element such as a diaphragm 13. A diagonally extending inlet passage 14 may be controlled by means such as an inwardly opening-valve at 15; and an outlet or fuel delivery passage 16 may be controlled by a similar valve 17. The illustrated means for reciprocating diaphragm 13 comprises a spring 18 conditionally operative to effect an intermittent expulsion of fuel from the chamber 12 past valve 17, such expulsion being dependent upon a pressure differential between chamber 12 and passage 16.

Any desired means such as a lost motion linkage 19, effective under tension but ineffective under compression, may be employed to impart an intake movement to the diaphragm 13, or its equivalent; but it will be understood that, although links 19 and 20 are respectively pivoted at 22 to a slidable element 23 (carrying a nut 24 for the retention of plates 25 and 25', by which the diaphragm 13 is shown as secured) and, at 26, to a lever 27, movable upon a pivot 28 by means such as any reciprocating or rotating engine-driven part, these details are of minor importance herein.

The closure plate or casting 11, shown as carrying an inserted valve seat 29 for the outlet valve 17, may carry also a slight-cup

or filter-cup 30, provided with any suitable filtering element,—the construction here referred to being such that fuel advancing through any feed pipe from any fuel tank, not shown, may be admitted by way of the cup 30 and past the intake valve 15.

Coming now to preferred details of the novel pulsator to whose protection the present application is directed, a hollow body 31, preferably adapted to receive a wrench or the like, is shown as externally threaded at 32 and is provided with an inclined or other duct 33, serving to establish constant communication between a passage 34 in said body and the outlet passage 16. The hollow body 31 is preferably provided not only with a downward extension 35, serving to retain and guide a spring 36 (tending to seat the valve 17) but also with means for supporting a non-resilient diaphragm 37.

For the purpose last referred to, and to provide a variable-volume auxiliary container 38, beneath the diaphragm 37 and in communication with the passage 34, an upwardly convex part 39 is shown peripherally secured to said diaphragm and mounted upon an upwardly extending reduced portion 40 of the body 31, the reduced portion being shown as swaged or headed down over the concave part 39, although a soldering or other equivalent operation might be here employed. An optional element may have the form of a downwardly concave part 41; and this part 41, shown as perforated at 42, may be adapted not only to serve as a guard element protecting the diaphragm 37, assuming the latter to be formed of cloth, suitably treated to render the same impervious to liquid fuels, but also peripherally to secure the upwardly convex part 39 (whether the latter is resilient or rigid) to the said diaphragm, or to any equivalent flexible but substantially inextensible diaphragm element, not resilient and not secured under such tension as to prevent it from responding to pressure differentials.

The coating and/or composition of the diaphragm 37, although there need be no novelty in the material or materials used, may be such as to obviate the requirement of any gasket in connection with a joint serving to secure the parts 37 and 39 together, as by the crimping or pressing of a peripheral edge of the guard element 41 thereover in the general manner suggested at 43; and it will be obvious that the construction here referred to is both simple and inexpensive as well as durable and reliable.

As to mode and theory of operation, the use of a slack-cloth diaphragm of the described character, eliminating all necessity for a resilient metallic diaphragm or for an air vesicle or any other resilient members as heretofore used, renders possible the utilization of the inertia of the liquid contained in the delivery line (as, between the described

pump and a carburetor, not shown) to keep the pumped liquid advancing. It is believed that a suction under the pulsator diaphragm tends to draw a limited quantity of liquid contained in the chamber 38, or its equivalent, through the duct 33 after the valve 17 closes, this movement being presumably aided by air pressure admitted through the perforation 42 and assuring a continuity in the flow toward the carburetor. In other words, the diaphragm 37 may rise within a pulsator of the described character during each expulsion stroke of the diaphragm 13, or an equivalent reciprocatory pumping element; and, notwithstanding such a prompt closure of the valve 17 as would otherwise interrupt the consequent flow of fuel through the outlet 16, the flexibility of the diaphragm 37, rendering the same especially sensitive to such pressure differentials as may occur when the need of fuel is greatest, may adapt the same promptly to descend upon the closing of the valve 17 in such a manner as to permit a substantially uniform flow, or at least an uninterrupted uni-directional flow, of fuel toward a carburetor of any suitable type (not shown).

It will be obvious that the described mode of operation involves a decreased peak pressure upon the pump diaphragm 13, thus allowing its spring 18 to move upward farther in a given length of time and to force a greater volume of liquid out past the valve 17; but no effort is at present made separately to evaluate the factors upon which the efficiency of the pulsator unit of the described general character may depend.

Although but a single type of pulsator illustrative of the principles of this invention is above described, it will be obvious that numerous additional forms might easily be devised by workers skilled in the art to which this relates,—without involving the slightest departure from the scope indicated above and in the following claims.

For the reason that fuel pumps of the type herein shown are commonly used to produce a pressure which never exceeds three pounds per square inch above atmosphere in the delivery line, no effort is herein made to fix the upper limit of absolute pressure above which a pulsator of the described type will cease satisfactorily to function; as indicated, the notable results obtained appear to be due mainly to inertia effects.

I claim:

1. For use in continuous communication with a line into which liquid fuel is intermittently delivered, an inertia-effect pulsator unit comprising: a hollow main body provided with a communicating passage; a part serving to support a diaphragm element from said body; and a non-resilient but flexible diaphragm carried by said supporting part and outwardly exposed to atmospheric pressure.

2. A pulsator as defined in claim 1 in which said main body is threaded suitably for use as a valve plug.

3. A pulsator as defined in claim 1 in which said diaphragm is a slack-cloth diaphragm.

4. A pulsator as defined in claim 1, in which said diaphragm is a slack-cloth diaphragm secured by a downwardly concave part which serves as a guard element there-
10 for.

5. A pulsator as defined in claim 1 in which said diaphragm is provided with a guard element having a constantly open aperture to admit air pressure thereto.

15 6. For use in an automobile fuel pump line, a flow-equalizing inertia-effect means comprising: a non-resilient diaphragm; and means for so securing said diaphragm as to admit the fluctuating pressure of a pumped
20 fuel to one side thereof while freely passing external air pressure to and from the other side thereof.

In testimony whereof I affix my signature.

LUCIAN B. SMITH.
